(57) **CLAIM**

The ornamental design for a fan, as shown and described.

DESCRIPTION

FIG. 1 is a left, front, top perspective view of a fan in accordance with the present invention;
 FIG. 2 is an elevation view of the front thereof;
 FIG. 3 is an elevation view of the rear thereof;
 FIG. 4 is an elevation view of the left side thereof;
 FIG. 5 is an elevation view of the right side thereof;
 FIG. 6 is a top plan view thereof;
 FIG. 7 is a bottom plan view thereof; and,
 FIG. 8 is right, front, bottom perspective view thereof.
 The broken lines illustrate portions of the fan that form no part of the claimed design.
